UNITED STATES PATENT OFFICE.

LUCENA M. MORDEN, OF WATERBURY, CONNECTICUT.

LOOSE-LEAF BINDER.

1,129,891.

Specification of Letters Patent.

Patented Mar. 2, 1915.

Application filed June 4, 1913. Serial No. 771,536.

To all whom it may concern:

Be it known that I, LUCENA M. MORDEN, a citizen of the United States, residing at Waterbury, in the county of New Haven 5 and State of Connecticut, have invented certain new and useful Improvements in Loose-Leaf Binders, of which the following is a specification.

This invention relates to loose leaf binders or devices, the object of the invention being to provide an improved structure of this kind in which the covers are provided with edges or flanges extending in the same general direction or plane as such covers 15 whereby they may be connected by suitable binding means to permit the loose leaf sheets held by the binding means to open flat and to be removed or inserted at any point without the removal of other sheets.

20 In the usual way of forming loose leaf binders of this general style the same are provided with flanges which are turned at right angles thereto, the binding means used therewith consisting of brads, tape, posts or wire, clamping the leaves so that they cannot open flat, neither can the leaves be removed at any point but only from the top or bottom of the pad of sheets held by them. If it is desired to remove a sheet from the 25 middle all sheets in front of it must be removed and replaced again after the desired sheet is taken out. The same thing applies in adding a sheet at any point other than the bottom or top. Therefore rings or arch-shaped holding devices cannot be used in a 30 practical manner therewith.

In the drawings accompanying and forming part of this specification, Figure 1 is an 35 end view of one form of the present improvement; Fig. 2 is an end view of a slightly different form thereof; Fig. 3 is an end view of another form thereof; Fig. 4 is a view of another form; Fig. 5 is a plan of the form shown in Fig. 4, and Fig. 6 illustrates a form of ring which may be used 40 in the present improvement connected to a portion of a sheet or leaf.

Similar characters of reference indicate 45 corresponding parts throughout the different figures of the drawings.

In the present improvement the covers 2 and 3 may have attached adjacent to their inner edges in any suitable way, a pair of flanges 4 and 5, one for each cover, both of 50 which flanges extend beyond the inner edges

7 of the covers in the same general direction or plane as such covers and into the back or binding portion 8 of the structure. In the form shown in Fig. 1 these flanges are attached as stated in any suitable way to the 60 covers although obviously the covers may be of sufficient width to form the flanges so that the back or binding portion 8 may overlap the same and be attached thereto, this being a mere reversal of the form shown in Fig. 1. 65

In the form shown in Fig. 2 it will be observed that the covers 9 and 10 are formed integral with the binding or back portion 11, being folded upon themselves at their inner edges to form the flanges 12. 70

In the form shown in Fig. 3 the flanges 13 and 14 are formed in a slightly different manner, they being flexibly connected to the covers 15 and 16 while the back or binder portion 17 is independently connected to the 75 covers themselves. In other words, the flanges in this form are flexibly connected with the back instead of being formed as one piece therewith as shown in Fig. 2 or overlapping and attached thereto as shown in 80 Fig. 1. This flexible joint can be obtained in a simple manner by connecting the flanges to the cover proper by suitable flexible material such as cloth or paper 18. In the form shown in Figs. 4 and 5 the flanges are 85 formed of metal thus providing a reinforcing edge for the inner edges of the covers or sides. In Fig. 4 the metal flanges 20 and 21 are shown carried in grooves or ways 22 of the metal binding edge, which is so folded 90 upon itself as to receive within it the edge 7 of the cover. The flanges in this case however may be formed as one continuous flange or as separated members or projections 23, as shown in Fig. 5, provided with slots preferably of angular form for the reception of 95 the rings.

When the inwardly extending flanges are formed as independent members as shown in Fig. 5 they may be so carried by the grooves 100 hereinbefore referred to as to be readily shifted along the same to any desired point; in other words, they are adjustable.

In the present structure shown the rings 24 are of angular stock and are therefore 105 received by slots 25 of angular formation. It will, of course, be understood that the flanges in the various forms shown will be provided with the necessary slots of the desired form to receive the rings. It will also 110

be understood that the various details may be more or less modified without departing from the scope of this improvement.

The provision of a ring of angular stock and slot to correspond results in a material advantage in that it will not pull out of the slot as a ring of round wire would, that is to say by reason of the angular slots, shoulders 30 and 31 are obtained which engage the inner face of the angular stock of the ring and so hold it in place against pulling out.

It will be observed that in the present improvement the flanges are in the same plane with the covers, that is to say the flanges project in the same general direction as do the covers.

It will, of course, be understood that instead of using the metal binding edge shown in Figs. 4 and 5, the shiftable projections 23 may be adjustable in grooves formed in the rear edges of the cover whether these grooves be formed by metal binding members or be formed directly therein, and obviously if the projections 23 were one continuous flange as shown for instance in Fig. 3, the entire flange could be detached with the leaves attached thereto as can also be the projections 23.

30 I claim as my invention:

1. A loose leaf binder comprising a pair of duplicate covers and a back portion connected to said covers at substantially the same distance from the inner edges thereof, said covers having inwardly extending flanges projecting within such back portion for the reception of binding rings, such flanges extending in the plane of the cover in both open and closed positions of said cover.

2. A loose leaf binder comprising a pair of covers, a back portion and a pair of flanges attached to such covers and both projecting within such back portion beyond the point of attachment of the back portion to the covers and both formed alike to receive binding rings therethrough, such flanges extending in the plane of the cover in both open and closed positions of said cover.

50 3. A loose leaf binder comprising a cover and a back portion, said cover having an inwardly extending inflexible flange projecting in the plane of the cover within such back portion for the attachment of binding rings thereto, such flange extending in the plane of the cover in both open and closed positions of said cover.

4. A loose leaf binder comprising one or more covers having a back portion attached thereto each of said covers having an inwardly extending flange projecting into such back portion and provided with slots for the reception of binding rings.

5. A loose leaf binder having one or more covers and a back portion, each of said

covers having an inwardly extending flange projecting into such back portion and having angular slots for the reception of rings formed of angular stock.

6. A loose leaf binder comprising a pair of covers and a back, each of said covers having a flange projecting into said back in the plane of its cover, said flanges having angular slots for the reception of binding rings formed of angular stock. 70

7. A loose leaf binder comprising one or more covers, a back, a metal member secured to the inner edge of each of said covers, and an inwardly extending flange for the reception of binding means, said member and flange one having a guideway and the other 80 slidable in said guideway. 75

8. A loose leaf binder comprising one or more covers, a back, a metal member secured to the inner edge of each of said covers, and an inwardly extending flange for the reception of binding means, said member and flange one having a guideway and the other 85 slidable in said guideway, said flange consisting of a plurality of independent projections. 90

9. A loose leaf binder comprising one or more covers, a back, a metal member secured to the inner edge of each of said covers and provided with an inwardly extending flange for the reception of binding means, said flange consisting of a plurality of independent projections, one or more adjustable relatively to a companion projection. 95

10. A loose leaf binder comprising one or more covers, a metal member secured to the inner edge of each of said covers and having a guideway and a flange slidable in said guideway and extending in the plane of its 105 cover, said flange being made up of a plurality of separated projections each having an opening for the reception of a binding ring.

11. A loose leaf binder comprising one or more covers, a metal member secured to the inner edge of each of said covers and provided with a flange extending in the plane of its cover and having openings for the reception of binding rings, said flange being made up of a series of projections adjustable one 110 relatively to another. 115

12. A loose leaf binder comprising one or more covers, a metal member secured to the inner edge of each of said covers and provided with a flange extending in the plane of its cover and having openings for the reception of binding rings, said flange being made up of a series of projections, each having an angularly formed slot for the reception of a binding ring of angular stock. 120

13. A loose leaf binder comprising one or more covers and a metal flange extending in the plane of each of said covers from the rear edge thereof and having one or more openings for the reception of binding rings, 125

said flange being made up of one or more projections adjustable lengthwise relatively to the cover.

14. A loose leaf binder comprising one or 5 more covers and a metal flange extending in the plane of each of said covers from the rear edge thereof and having one or more openings for the reception of binding rings, said flange being made up of one or more 10 projections adjustable lengthwise relatively to the cover, and said cover having along its rear edge a groove for the reception of said projection.

15. A loose leaf binder comprising one or 15 more covers and a flange projecting from the rear edge of each of said covers in the plane of said cover, said flange and cover having one a part overlapping the other for sliding movement one relatively to the other.

20 16. A loose leaf binder comprising one or more covers and a flange projecting from the rear edge of each of said covers in the plane of said cover, said flange and cover having one a part overlapping the other and 25 said flange comprising one or more projections adjustable lengthwise relatively to the cover, each of said projections having an opening for the reception of a binding ring.

20 17. A loose leaf binder comprising one or 20 more covers and a flange projecting from the

rear edge of each of said covers in the plane of said cover, said flange and cover having one a part overlapping the other and said flange comprising one or more projections adjustable lengthwise relatively to the cover, each of said projections having an opening 35 for the reception of a binding ring, said cover and projections being formed of different materials.

18. A loose leaf binder comprising one or 40 more covers and a flange projecting from the rear edge of each of said covers in the plane of said cover, said flange and cover having one a groove for slidably carrying 45 the edge of the other, said flange having one or more slots for the reception of a binding ring or rings.

19. A loose leaf binder comprising one or more covers and a flange projecting from the rear edge of each of said covers in the plane 50 of said cover, said flange and cover having one a groove for the reception of the edge of the other, whereby said flange may be detachable from its cover, said flange having one or more slots for the reception of a binding 55 ring or rings.
